UNITED STATES PATENT OFFICE.

MORRIS H. MARCUS, OF EDENBURG, ASSIGNOR, BY DIRECT AND MESNE ASSIGNMENTS, OF ONE-HALF TO LEOPOLD A. KATZ, OF BRADDOCK, PA.

SAMPLE-DUMMY.

SPECIFICATION forming part of Letters Patent No. 290,188, dated December 11, 1883.

Application filed March 22, 1883. (No model.)

To all whom it may concern:

Be it known that I, MORRIS H. MARCUS, of 5
Edenburg, in the county of Clarion and State
of Pennsylvania, have invented certain new
and useful Improvements in Sample-Dummies,
of which the following is a full, clear, and exact
description.

This invention relates to dummies for cloth
or rolled goods in continuous or store use, as
10
distinguished from silk or other similarly-
folded goods for window-show only, and which
it has been proposed to exhibit by covering a
dummy with a piece of the goods representing
a bolt of the same.

15 The invention consists in a dummy for cloth
or rolled goods, made of wood or other suitable
material, with its body of the required
shape of the roll of goods to be represented,
and having reduced ends, on which are secured
20 and mounted or wrapped pieces of selvage
till a bulk is obtained equal to that of the body
of the dummy, that, as also the mounted
selvages on its ends, is covered by a piece of
the goods, thus representing a solid roll of
25 cloth or goods upon a block of the size of the
exposed reduced ends of the dummy.

Reference is to be had to the accompanying
drawings, forming part of this specification, in
which similar letters of reference indicate cor-
30 responding parts in all the figures.

Figure 1 represents a view in perspective of
a sample-dummy of rolled goods in accordance
35 with my invention. Fig. 2 is a longitudinal
section of the same in a plane which is
perpendicular to the thickness of the dummy;
and Fig. 3, an end view of the dummy in its
bare or uncovered condition.

A in the drawings indicates the body of the
dummy, of oblong shape in direction of its
40 length and of greater width than thickness,
with its edges rounded, as at *a a*, and formed
with narrow central reduced end portions, *b b*,

of like contour with the body A. The whole
length of the dummy, including its reduced
ends, should be equal to the width of the cloth
45 or goods to be exposed, or thereabout. Upon
each of these reduced ends *b* is wrapped or
rolled, and secured either by gluing, tacking,
or otherwise, a strip or strips of selvage, B,
which is mounted upon each of said ends till
50 the same comes up to the level and corresponds
with the size of the body A at its ends. Said
body A and selvage wrappings B at its
ends are then covered by one or more thicknesses
55 of the cloth or goods C the covered dummy
is designed to represent a sample of,
and the same secured in place by the usual
straps, *d d*, or other fastenings. The covered
dummy will then represent a solid roll of
60 cloth or goods upon a block of the size of the
reduced ends *b* of the dummy.

A sample-dummy thus constructed will be
found of great service to merchant tailors and
other store-keepers, especially new beginners
or those having but a limited amount of capital
65 at command, inasmuch as while they will
have a large amount of samples in roll form
to display which will attract customers, the
expense of carrying a heavy load of goods is
70 avoided, and the loss in case of fire will be
comparatively small.

Having thus described my invention, what
I claim as new, and desire to secure by Letters Patent, is—

In a dummy for samples, the combination, 75
with the body A and its central reduced ends,
b b, of the selvages B B, secured to and mounted
upon said ends, substantially as shown, and
for the purposes herein set forth.

MORRIS H. MARCUS.

Witnesses.
